UNITED STATES PATENT OFFICE.

ADOLF GRANLUND, OF ESCANABA, MICHIGAN.

STUMP-EXTRACTOR.

1,112,998.

Specification of Letters Patent.

Patented Oct. 6, 1914.

Application filed May 2, 1914. Serial No. 935,998.

To all whom it may concern:

Be it known that I, ADOLF GRANLUND, a citizen of the Kingdom of Sweden, residing at Escanaba, in the county of Delta and State of Michigan, have invented certain new and useful Improvements in Stump-Extractors, of which the following is a specification.

The present invention relates to improvements in stump extractors, the object in view being to provide a simple and compact structure of this character designed to facilitate manipulation of the same and so arranged as to afford a maximum amount of power for extracting purposes.

In carrying out the invention I provide in combination with a cable or similar flexible member, one end of which is adapted to be connected or anchored to a stationary object, a movable member in the form of a running pulley operably connected to the stump to be extracted and around which the cable passes, the other end of said cable being secured to tension means also coöperating with the cable intermediate the pulley aforesaid and the stationary member and embodying actuating means therefor to cause movement of said tension means toward the stationary object and thereby exerting tension through the running pulley on the stump to be extracted.

A still further object in mind is the provision of tension means as hereinbefore mentioned of a special character embodying a toothed drum about which the cable is wound and which is mounted in a frame through which said cable passes, together with actuating means for the drum for imparting rotation to the same to cause the tension means to move on the cable, when said cable is wound around the drum in either direction.

These and such other objects as may hereinafter appear are attained by the novel construction, combination, and arrangement of parts to be hereinafter specifically described and claimed.

Reference will now be had to the accompanying drawings forming a part of this specification, wherein:

Figure 1 is a perspective view of an apparatus embodying my invention in position for performing its extracting function. Fig. 2 is a side elevation of the device. Fig. 3 is a top plan view. Fig. 4 is a longitudinal sectional view through the tension means on

the line 4—4 of Fig. 3. Fig. 5 is a transverse sectional view on the line 5—5 of Fig. 3, showing the cable partly broken away; and Fig. 6 is a perspective view showing the details of the actuating means for the toothed drum of the tension means of this device.

Throughout the following detail description, and on the several figures of the drawings, similar parts are referred to by like reference characters.

Specifically describing my extracting apparatus and referring to the drawings, the numeral 1 designates a cable or similar flexible member, one end of which is connected to a stationary object 2 located near the stump 3 which is to be extracted. The cable 1 passes about a movable member in the form of a running pulley 4 which is operably connected to the stump and said cable at its other end is positively secured to the frame 5 of the tension means or mechanism of this device now to be more particularly described.

As most clearly shown in Figs. 1 and 5 of the drawings, the tension means just mentioned is interposed between the pulley 4 and the stationary object 2, the cable 1 passing about a toothed drum 6 mounted upon the vertical axis 7 between laterally projecting spaced arms 8 of the frame 5.

Referring particularly to Fig. 5 the frame 5 consists of opposite U-shaped arms or members 5' and 5'' each of which has an opening therethrough as indicated at 9 and 9' and when the cable is in operable position, starting from the end secured to the stationary object 2, it passes through the opening 9' around the toothed drum 6 several times and from thence through the opening 9 about the pulley 4 and back again to the U-shaped arm 5' of the frame to which it is positively secured forming a stress exerting loop at this end. Between spaced arms 10 extending from the frame at the side opposite to the arms 8 between which the drum 6 is mounted, is pivoted an operating lever 11, the pivot 12 passing through the bifurcated terminal of said lever as shown most clearly in Figs. 1 and 4. Between the bifurcate ends of the lever 11 is mounted at one side a hooked pawl 13, the hooked terminal of which is adapted to engage with the teeth 14 formed on the peripheral edge of said drum while at the opposite side is similarly mounted a stop pawl

15 also adapted to coöperate with the teeth 14 to hold the drum at any adjusted position. A spring 16 is disposed upon the pintle 17 extending through the lever 11 and has one terminal thereof coöoperating with the hooked pawl 13 adjacent the pivot 13' of the same, while the other end of said spring coöperates with the stop pawl 15 adjacent its pivot 15', the common tension element 10 thus provided maintaining these pawls in co-operation with the toothed drum under normal conditions.

Having thus described the invention, its operation will now be particularly pointed out.

The pulley 4 having been operably connected to the stump 3 in any desired manner the lever 11 is oscillated to and fro so as to cause the hooked pawl 13 to rotate the drum 6 in the direction indicated by the arrow in Fig. 3. The stop pawl 15, when the lever is moved in a direction drawing the pawl 13 toward the pivot of said lever, rides on the teeth 14 on the drum until the limit of movement of said lever is reached when it interlocks with the drum and enables the pawl 13 to further actuate said drum upon imparting to said lever a similar movement after having reengaged the pawl 13 with teeth farther around on the periphery of said drum. Movement of the drum as just described causes the cable 1 to be wound thereupon in one direction and to be unwound therefrom an equal extent in the other direction, which action imparts movement to the tension means in an obvious manner, and by reason of the fact that one extremity of said cable is secured to the frame of the tension means, tension is imparted to the pulley 4, tending to cause said pulley to move in a similar direction toward the stationary object 2. By reason of the winding of the cable about the drum 6 and the leverage afforded by the lever 11 a considerable power is afforded the device enabling the stump to be extracted and it will be obvious to those skilled in this art that the travel of the tension means along the cable will be twice as fast or as great as the corresponding movement of the pulley 4 in the same direction. As long as the lever is oscillated the movement of the tension device will take place until the stump has been extracted and when it is again desired to set the apparatus in position for a subsequent extracting operation the pawls 13 and 15 are adapted to be held out of engagement with the teeth of the drum 6 by means of hooks 17' and 18 secured at opposite sides of the lever 11 at 50 17' and 18' respectively. Each pawl for this purpose is provided with an eye 19, 19' in which the respective hooks are engaged as shown most clearly in dotted lines in Fig. 3 of the drawings. When the pawls are thus 65 disengaged from the drum 6 the lever 11 is

moved into a position in alignment with the arms 8 of the frame 5 and a set screw or similar locking member 20 is screwed into engagement with a recess 21 in a bifurcate terminal of said lever which recess is shown 70 in Figs. 4 and 6 respectively. By exerting a pull upon the pulley 4 the tension means or mechanism will be moved by unwinding of the cable in the direction in which the pull on the pulley is exerted. The pawls are 75 then allowed to engage with the drum again and the lever 11 unlocked so that the actuation of the device may be accomplished in a manner described hereinbefore. The lever 11 preferably consists of the socket 11' and 80 the removable handle 11'' which latter may be of any suitable length depending upon the amount of leverage which is required for operation of the device.

As a matter of convenience, I preferably 85 provide eyes 22 and 23 at opposite sides of the lever 11 in which the hooks 17 and 18 may be disposed when in inoperative position and during the use of the ratchet mechanism. I also specially form the spring 16 90 with bent terminals and these terminals are adapted to coöperate with the eyes 19, 19' of the pawls 13 and 15 respectively so as to limit movement of the lever in opposite directions, said spring and eyes mentioned 95 thus performing a dual function.

It will be apparent to those skilled in this art that the invention hereinbefore described may readily be used for various other purposes than that incidental to the extracting 100 of stumps and in fact wherever it is desired to employ power mechanism for imparting tension to objects as when lifting, drawing and in similar operations. In addition to this fact it will be understood that changes 105 may readily be made in the details of construction of this device and particularly of the tension means comprehended by the foregoing description without departing from the spirit of the invention and within the 110 scope of the claims hereto appended.

Having thus described my invention, what I claim as new is:

1. In an extracting device of the class described, the combination of a cable adapted 115 to be fixed at one end portion to a stationary object, tensioning means engaging an intermediate portion of the cable, the other end portion of the cable being fixed to the tensioning means to form a stress exerting 120 loop beyond the tensioning means, and means for actuating the tensioning means for causing the same to travel toward the stationary object.

2. In an extracting device of the class described, the combination of a cable adapted 125 to be fixed at one end portion to a stationary object, tensioning means engaging an intermediate portion of the cable, the other end portion of the cable being fixed to the ten- 130

sioning means to form a stress exerting loop beyond the tensioning means, a pulley about which said loop extends, means of connection for the pulley with the object to be extracted, and means for actuating the tensioning means for causing the same to travel along the cable toward the stationary object.

3. In an extracting device of the class described, the combination of a cable adapted to be connected at one end to a stationary object, a movable member operatively connected to the object to be extracted and around which the cable passes adjacent its other end, tensioning means to which the last mentioned end of the cable is connected whereby to form a stress exerting loop, said tensioning means embodying a frame through which the cable passes intermediate the movable member and the stationary object, and means for actuating said tensioning means to cause the same to move on the cable toward a stationary object and thereby exert tension upon the movable member aforesaid.

25 4. In an extracting device of the class described, the combination of a cable adapted to be fixed at one end portion to a stationary object, tensioning means comprising a capstan engaging an intermediate portion of the cable, the other end portion of the cable being fixed to the tensioning means to form a stress exerting loop beyond the tensioning means, and means for actuating the tension means for causing the same to travel toward the stationary object.

5. In an extracting device of the class described, the combination of a cable adapted to be connected to a stationary object at one end, said cable being connected with an object to be extracted, a drum engaging an intermediate portion of the cable, a frame in which the drum is mounted and to which the second end of the cable is connected, means for actuating the drum to cause the frame and drum to move along the cable toward a stationary object, and means coacting with the last mentioned means and locking the frame drum against movement toward the object to be extracted when the drum is actuated by the actuating means aforesaid, said locking means being releasable to permit free movement of the frame and drum on the cable away from the stationary object.

6. In an extracting device of the class described the combination of a cable adapted to be connected to a stationary object, means connecting the cable to an object to be extracted, and tension means engaging an intermediate portion of the cable and comprising a frame having apertures therethrough through which the cable passes, a drum mounted on said frame intermediate the apertures for said cable around which

the cable is wound, means for actuating said drum, comprising a lever pivoted to the frame, an actuating pawl carried by the lever for rotating the drum, and a locking member on said lever coöperating with said drum for locking the same against movement in one direction.

7. In an extracting device of the class described, the combination with a cable adapted to be connected to a stationary object at one end, tension means coöperating with said cable intermediate its length and operatively connected to an object to be extracted, said tension means comprising a frame through which the cable passes, a pulley disposed intermediate the object to be extracted and the tension means and around which the cable passes in the form of a loop, the loop end portion of said cable being connected to the frame aforesaid, a toothed drum mounted in said frame about which the cable is wound, a lever pivotally secured to said frame, an actuating pawl pivotally mounted on said lever and adapted to engage the toothed drum to impart rotation thereto upon oscillation of said lever, a locking pawl coöperating with the drum to hold the same at adjusted positions, and means for holding the pawls disengaged from the drum to permit free rotation of the same.

8. In an extracting device of the class described, the combination with a cable adapted to be connected to a stationary object at one end, tension means coöperating with said cable at an intermediate point and operatively connected to an object to be extracted, said tension means comprising a frame through which the cable passes, a pulley disposed intermediate the object to be extracted and the tension means and around which the cable passes in the form of a loop adjacent its other end, the loop end of said cable being connected to the frame aforesaid, a toothed drum mounted in said frame about which the cable is wound, a lever pivotally secured to said frame, an actuating pawl pivotally mounted on said lever and adapted to engage the toothed drum to impart rotation thereto upon oscillation of said lever, a locking pawl coöperating with the drum to hold the same at adjusted positions, means for holding the pawls disengaged from the drum to permit free rotation of the same, and independent means for locking the lever against movement when the pawls are disengaged from the drum.

9. In an extracting device of the class described, the combination with a cable adapted to be connected to a stationary object at one end, tension means coöperating with said cable and operatively connected to an object to be extracted, said tension

means comprising a frame through which the cable passes, a pulley disposed intermediate the object to be extracted and the tension means and around which the cable 5 passes, one end of said cable being connected to the frame aforesaid, a toothed drum mounted in said frame about which the cable is wound, a lever pivotally secured to said frame, an actuating pawl pivotally 10 mounted on said lever and adapted to engage the toothed drum to impart rotation thereto upon oscillation of said lever, a locking pawl coöperating with the drum to hold the same at adjusted positions, and 15 spring tension means common to the actuating pawl and the locking pawl normally maintaining said pawls in engagement with the drum.

10. In an extracting device of the class 20 described, the combination with a cable adapted to be connected to a stationary object at one end, tension means coöperating with said cable and operatively connected to an object to be extracted, said tension means 25 comprising an apertured frame through which the cable passes, a toothed drum mounted in said frame and around which the cable is wound, a lever for actuating the drum to cause movement of the tension 30 means along the cable, an actuating pawl connected to the lever and coöperating with the drum to rotate the same upon oscillation of said lever, a locking member carried by said lever and coöperating with the drum 35 to hold the same at adjusted positions, a spring mounted in said lever and having its terminals bearing against the actuating pawl and the locking member aforesaid to normally hold the same in engagement with the drum, a hook member carried by 40 the lever at each side of the same and adapted to be engaged with the actuating pawl and the locking member respectively to hold the same out of engagement with the drum, and to thereby permit free rotation of said 45 drum, a locking member mounted in the frame and adapted to engage with the lever to lock said lever against movement relative to the frame when the pawls are disengaged from the drum, and abutment members on the actuating pawl and the locking member aforesaid adapted to limit the movement of the lever in either direction, said abutment members consisting of eyes disposed to contact with the 50 lever in either direction, said hook members carried by the lever being adapted to be engaged in the eyes aforesaid for holding the actuating pawl and locking member out of engagement with the drum.

member aforesaid adapted to limit the movement of the lever in either direction.

11. In an extracting device of the class described, the combination with a cable 55 adapted to be connected to a stationary object at one end, tension means coöperating with said cable and operatively connected to an object to be extracted, said tension means comprising an apertured frame 60 through which the cable passes, a toothed drum mounted in said frame and around which the cable is wound, a lever for actuating the drum to cause movement of the tension means along the cable, an actuating 65 pawl connected to the lever and coöperating with the drum to rotate the same upon oscillation of said lever, a locking member carried by said lever and coöperating with the drum to hold the same at adjusted positions, a spring mounted in said lever and having its terminals bearing against the actuating pawl and the locking member aforesaid to normally hold the same in engagement with the drum, a hook member carried by the lever at each side of the same and adapted to be engaged with the actuating pawl and the locking member respectively to hold the same out of engagement with the drum to thereby permit free rotation of said drum, a locking member mounted in the frame and adapted to engage with the lever to lock said lever against movement relative to the frame when the pawls are disengaged from the drum, and abutment 75 members on the actuating pawl and the locking member aforesaid adapted to limit the movement of the lever in either direction, said abutment members consisting of eyes disposed to contact with the lever in either direction, said hook members carried by the lever being adapted to be engaged in the eyes aforesaid for holding the actuating pawl and locking member out 80 of engagement with the drum.

In testimony whereof I affix my signature in presence of two witnesses.

ADOLF GRANLUND.
